United States Patent Office.

FREDERICK WOOD, OF BRIDGEPORT, CONNECTICUT.

Letters Patent No. 69,291, dated September 24, 1867.

IMPROVEMENT IN SECURING WHIP-SOCKETS TO CARRIAGES.

The Schedule referred to in these Letters Patent and making part of the same.

TO ALL WHOM IT MAY CONCERN:

Be it known that I, FREDERICK Wood, of Bridgeport, in the county of Fairfield, and State of Connecticut, have invented a new Mode of Securing Whip-Sockets to Carriages; and I do hereby declare the following, when taken in connection with the accompanying drawings and the letters of reference marked thereon, to be a full, clear, and exact description of the same, and which said drawings constitute part of this specification, and represent, in—

Figure 1, a top view.

Figure 2, an edge view.

Figures 3 and 4, the two parts, the one turned from the other to show the inside of the connection.

Figure 5 the two parts detached, and in

Figure 6 as set together.

This invention relates to an improvement in the clasp which is used for securing whip-sockets to carriages, and consists in the peculiar construction of the two parts of the clasp so as to attach the socket to a horizontal bar, as the rail of a coach-seat, and without other connection than that employed for securing the two parts together.

In order to the clear understanding of my invention, as well as to enable others to construct the same, I will proceed to a description thereof, as illustrated in the accompanying drawings.

A is the one part and B the other part, each provided with a prong, C, the one turning to the right, the other to the left, so as to nearly or quite encircle the socket. The two parts A and B have similar but smaller prongs D, at right angles to A and B, as seen in fig. 2, which encircle the horizontal bar. The two parts A and B have formed upon their meeting surfaces a groove, a, upon one part, a corresponding V, d, on the other part, and an incline, f, on both parts, as seen in fig. 5, so that when set together, as in fig. 6, the incline and V tend to draw the two parts together, so that the screw E, or an equivalent therefor, inserted through the two parts, secures them firmly together, as seen in figs. 1 and 2. To attach the socket, open the two parts and place the prong C around the socket, and the prongs D around the horizontal bar at the proper point, then secure the two parts together by the insertion of the screw E, or otherwise, and the socket is securely and firmly held in a neat and durable manner.

Having thus fully described my invention, what I claim as new and useful, and desire to secure by Letters Patent, is—

The herein-described clasp for securing whip-sockets, constructed so as to be attached and united in the manner set forth, as an improved article of manufacture.

FREDERICK WOOD.
